UNITED STATES PATENT OFFICE.

SAMUEL DARLING, OF PROVIDENCE, RHODE ISLAND.

INKSTAND.

SPECIFICATION forming part of Letters Patent No. 366,206, dated July 12, 1887.

Application filed May 26, 1887. Serial No. 239,497. (No model.)

To all whom it may concern:

Be it known that I, SAMUEL DARLING, a citizen of the United States, residing at Providence, in the State of Rhode Island, have invented a new and useful Improvement in Inkstands, of which the following is a specification.

My invention relates especially to that class of inkstands which are provided with an elastic ink-fountain, and the object of my invention is to simplify the construction of such inkstands and to adapt the same for being carried in the pocket; and it consists in making the top and bottom portions of the fountain-case in separate parts, which are connected by means of screw-threads, whereby upon revolving one of the said parts upon the other the vertical height of the chamber which holds the ink-fountain will be either increased or diminished, thereby operating upon the ink-fountain to cause the increase or diminution of the ink-supply in the dip-cup, as desired; and in an inkstand having an elastic ink-fountain, a dip-cup or dipping-aperture, a case for holding the fountain, the said case having a screw-thread upon its inner surface, and a bottom plate or follower provided at its periphery with a screw-thread fitting the inner screw-thread of the case and adapted by rotary movement to change the vertical height of the chamber for the ink-fountain, and thus control the ink supply in the dip cup or aperture; and also in providing the closing screw-cap of the inkstand with a pivoted stopper, whereby the rubber packing will be prevented from injurious wear or abrasion and a perfectly-tight joint will be obtained.

Figure 1 is a vertical section of my improved inkstand. Fig. 2 is an under view of the bottom plate or follower.

In the accompanying drawings, A represents the top and side portion of the case, which is provided with an interior screw-thread, *a*; and B the bottom plate or follower, provided at its periphery with the screw-thread *b*, which fits the screw-thread *a* of the upper portion of the case. The bottom plate or follower, B, is provided with a central opening, *c*, which is adapted to receive the bulging bottom portion 50 of the ink-fountain C, and with the opposite

lugs *d d*, by means of which the proper rotation of the bottom plate, B, is effected.

The ink-fountain C is made of india-rubber and provided with a neck, *e*, by means of which it is to be secured to the portion A of 55 the case. The neck *e* of the ink-fountain passes upward through the central opening, *f*, in the top of the case, and is secured therein by means of the forcible insertion of the stem *g* of the dip-cup D, which serves to press the elastic 60 neck of the fountain firmly against the wall of the opening *f*. The upwardly-projecting neck or flange *h*, which surrounds the opening *f*, is provided with an external screw-thread, *i*, which is adapted to receive the interior screw-thread, *j*, of the closing-cap E; and at the upper interior portion of the cap E is pivoted the stopper G, which serves to form a tight joint 65 at the upper edge or surface of the dip-cup, to prevent leakage.

The holding-case *k* of the stopper is loosely secured to the lower side of the top of the cap E by means of the screw *m*, which thus forms a swivel-connection between the case *k* and the cap, whereby the stopper can be rotated 70 upon the pivot-screw *m*, and also have a slight rocking movement, so that the rubber packing-disk *n*, held in the case *k* of the stopper, can readily adjust itself to a proper seat upon the edge of the cavity *o* of the dip-cup when the 75 cap E is being screwed upon the neck or flange *h* to close the inkstand, thus preventing the ink from leaking from the same into the pocket in which it is carried. The top of the cap E is preferably rounded upward at its central 80 portion, *p*, to form a spherically-concave seat for the spherical protuberance *q* upon the upper surface of the holding-case *k* of the stopper, which is thus socketed in the cap E.

The cavity *o* in the dip-cup to receive the 85 ink is slightly tapering, and at its lower end is placed the removable pen-gage *r*, which serves to limit the downward movement of the pen when dipping for the ink, the opening *s* at the lower side of the pen-gage being made 90 of less diameter than the width of the writing-pen.

When filling the fountain with ink, the pen-gage can be removed upward from the cavity *o* by means of a hook or otherwise. The upward 95

movement of the bottom plate or follower, B, by means of the relative rotation of the screw-threaded portions of the case, will cause the compression of the elastic ink-fountain C, and 5 force the ink upward into the cavity o of the dip-cup, and a reverse rotative movement of the screw-threaded portions will cause the withdrawal of the ink from the said cavity.

I claim as my invention—

- 10 1. An inkstand having an elastic ink-fountain, a dip-cup, and a case made in separate parts, which are connected by means of opposite screw-threads, whereby upon revolving one of the said parts upon the other the vertical 15 height of the chamber which holds the ink-fountain will be either increased or diminished, substantially as and for the purpose specified.
2. An inkstand having an elastic ink-fountain and a case for holding the ink-fountain, 20 the said case having a screw-thread upon its

inner surface, the bottom plate or follower being provided upon its periphery with a screw-thread fitting the inner screw-thread of the case and adapted by rotary movement to 25 change the vertical height of the chamber for the ink-fountain, substantially as and for the purpose specified.

3. An inkstand having a case or frame with a neck or flange provided with a screw-thread 30 upon its exterior surface, an elastic ink-fountain and means for compressing the same, a dip-cup or dipping-aperture, a screw-cap fitting the exterior screw-thread of the neck or flange, and a stopper pivoted in said cap and 35 adapted to close the dipping-aperture, substantially as described.

SAML. DARLING.
